UNITED STATES PATENT OFFICE.

LEWIS E. YOUNIE, OF PORTLAND, OREGON.

MECHANISM FOR CAR TRUCKS.

Application filed June 16, 1925. Serial No. 37,490.

This invention is designed to improve the mechanism for car trucks and is particularly useful where steep grades and sharp turns are encountered. The invention involves a 5 fluid-actuated lift between the frames carried by the wheels and the bolster and an arrangement of brake shoes carried by the bolster so that so long as the fluid-actuated lift is in operation and supports the bolster 10 the brake shoes are maintained out of engagement but as the fluid is exhausted from the lift the full weight of the load through the lowering of the bolster is delivered through the brake shoes directly to the 15 brake. The amount of braking may, of course, be regulated by relieving a greater or less amount of the fluid pressure on the lift. In order to readily take care of sharp turns the side frames of the truck are 20 swivelled on the bolster. Features and details of the invention will appear from the specification and claims.

The invention is illustrated in the accompanying drawings as follows:—

25 Fig. 1 shows a plan view of a logging truck supplied with the braking mechanism.

Fig. 2 an end view, partly in section, on the line 2—2 in Fig. 1.

30 Fig. 3 a side elevation, partly in section, on the line 3—3 in Fig. 1.

1 marks the track rails, 2 the wheels of the truck, 3 axles on the wheels, and 4 journal bearings for the axles.

5 marks the side frames, these side frames 35 comprising beams 5^a at each side of the wheels resting on the bearings, these beams being connected by a strap 5^b. A cylinder 6 has a flange 7 which is mounted between the beams 5^a, the flange resting on the tops 40 of the beams.

A bolster 8 is made up of the side webs 9, top channels 10 which are secured between the side webs 9 and extend outwardly over the side frames 5. Angle plates 11 are vertically arranged on the ends of the webs 9 and secured to the channels 10. Channels 13 extend from the lower sides of the webs 8 and within the angle plates 11 and under the side frames 5. The outer ends of the channels 13 45 are connected with the channels 10 by the posts, or connecting frames 14. Pistons 15 operate in the cylinders 6, the pistons having flanges 16 which are secured to the under sides of the channels 10. The pistons and 50 cylinders form a swivelled connection between the bolsters and side frames permit-

ting a slight swinging movement of the side frames relatively to the bolsters so that they may swing to conform to inequalities in the track. Thus the truck will follow readily a 60 very uneven track.

Fluid under pressure is supplied through pipes 17 leading through the pistons to the cylinders 6, said pipes being connected with the train pipe 18.

65 Brake shoes 19 are secured to the lower sides of the channels 13 and are arranged directly over the tracks.

There is a slight clearance between the tops of the channels and the bottoms of the 70 side frames so that when the pressure is on the cylinders, the pistons are lifted carrying the bolster 8 upwardly bringing the channels 13 into contact with the under sides of the frame and at the same time lifting the 75 brake shoes 19 off the track. The pressure in the cylinders is handled from the train line either with air or a liquid as may be more convenient so that in the normal running the brakes are clear of the track. When 80 it is desired to affect the braking action pressure is reduced on the line allowing a part of the weight of the train load to be carried by the direct engagement of the brake shoes with the brake. By completely exhausting 85 the cylinders the entire load may be thrown on the brake shoes thus affecting a maximum braking action.

As shown the system is adapted to a logging truck which has the usual coupling devices 20—21.

90 What I claim as new is:—

1. In a braking mechanism for car trucks, the combination of wheels; side frames carried by the wheels; a bolster; a track brake shoe carried by the bolster; and a fluid-actuated lift between the side frame and the bolster normally holding the brake shoe out of braking position and operable to permit the lowering of the brake shoe into engagement.

2. In a braking mechanism for car trucks, the combination of wheels; side frames carried by the wheels; a bolster; a track brake shoe carried by the bolster; and a fluid-actuated lift comprising a cylinder, and a piston, said piston forming a swivelled and sliding connection between the bolster and frame normally holding the brake shoe out of braking position and operable to permit the lowering of the brake shoe into engagement.

3. In a braking mechanism for car trucks, the combination of a pair of wheels at each side of the truck; a side frame at each side of the truck supported by said wheels; a bolster extending across the truck from side frame to side frame; a brake shoe carried by the bolster; and a fluid-actuated lift between each side frame and the bolster, normally holding the brake shoe out of braking position and operable to permit the lowering of the brake shoe into braking position. 25
4. In a braking mechanism for car trucks, the combination of a pair of wheels at each side of the truck; a side frame at each side of the truck supported by said wheels; a bolster extending across the truck from side frame to side frame; a brake shoe carried by the bolster; and a fluid-actuated lift between each side frame and the bolster, normally holding the brake shoe out of braking position and operable to permit the lowering of the brake shoe into braking position, said lift comprising a cylinder and piston forming guiding and swivelled connections between the side frames and the bolster. 30
5. In a braking mechanism for car trucks, the combination of a pair of wheels at each side of the truck, said frames carried by the wheels, said side frames comprising beams each side of the wheels and a cylinder between the beams; a bolster extending from side frame to side frame, said bolster having a piston extending into the cylinder; and brake shoes carried by the bolster. 35
6. In a braking mechanism for car trucks, the combination of a pair of wheels at each side of the truck; side frames mounted on the wheels; a bolster extending from side frame to side frame, the side frame extending through the ends of the bolster; a lift 40 connection between the bolster and the side frames comprising cylinders and pistons; and brake shoes carried by the bolster.

In testimony whereof I have hereunto set my hand.

LEWIS E. YOUNIE.
